PARKER J. O'BRIEN, OF BROOKLYN, NEW YORK

FLEXIBLE BAND FOR KNICKERS

Application filed March 15, 1930. Serial No. 436,132.

This invention relates to flexible bands and particularly to devices of this class adapted for use at the lower ends of the leg portions of knickers or other body garments and which may, if desired, be used as cuffs for shirts, sweaters and the like; and the object of the invention is to provide a band of the class specified consisting of a tubular body of woven or knitted material which is so woven 10 as to produce elasticity thereto, permitting circumferential expansion or flexure and serving to maintain the same firmly about the body of the wearer when in use; a further object being to provide a device of the class 15 specified wherein the extending or unattached portion of the cuff or band is composed of two ply thickness, one end of the cuff or band being folded within the other end in such manner as to leave a free projecting end at 20 the outer tubular portion, by means of which the device may be attached to or joined with a suitable body garment, the inner part of 25 the cuff or band being attached to the outer part by an extensible and preferably invisible stitch at a point inwardly of the free end of the outer part; a further object being to provide a device of the class specified wherein the single projecting flange portion of the device will facilitate the attachment to the garment 30 or other support and also present lighter elastic tensional engagement of the device with the garment; a further object being to provide a device of the class specified wherein the attaching flange portion thereof is 35 knitted in flared relation with respect to the remainder thereof, thus facilitating its attachment to the garment; and with these and other objects in view, the invention consists in a device of the class and for the purpose 40 specified which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a side view of a pair of knickers

illustrating one of my improved cuffs or bands mounted in connection therewith.

Fig. 2 is a side and sectional detail view of a part of the construction shown in Fig. 1; and,

Fig. 3 is a view similar to Fig. 2 showing only a part of the construction and showing a modification.

For the purpose of illustrating one use of my invention or one method of carrying the same into effect, I have indicated at 5 in Fig. 1 of the drawing a pair of knickers, the lower end portion of each of the legs of which has a leg encircling band 6. As seen in Figs. 1 and 2 of the drawing, 7 represents one form of my improved cuff or band which is fashioned from suitable material, preferably woolen fabric knitted into tubular form and in such manner as to provide a highly elastic tubular body, one end of which is knitted to 65 form a flare or enlarged attaching flange portion 8.

The other end portion 9 is folded within the outer part 10 of the cuff and the free inner edge 9a of the part 9 is stitched to the part 10 as seen at 11 at a point below the flange 8, or inwardly of the upper free edge of the outer part made up of parts 8—10 by a stitching which will permit free expansion and contraction of the cuff and also 80 stitching which is invisible when viewed externally of the cuff.

After fashioning the device and assembling the parts 9 and 10 thereof in the manner set forth, the same may be attached to the leg band 6 of the knickers or the free edge of a garment of any kind or class by a line of stitching 12 or in any other desired manner. In the construction shown, the flange 8 is arranged externally of the band 6 but this arrangement of the parts is not essential.

It will be noted that when the cuff or band 7 is attached, the upper edge 9a of the part 9 thereof is arranged below the lower edge of the band 6, thus providing a free flexure of the band 7 with respect to the band 6 through the attaching flange 8, by virtue of the flaring of said band and the fact that it involves a single ply thickness of the entire device. It will be apparent that the elasticity of the

single ply is materially less than that of the double ply consisting of the parts 9 and 10. It will therefore be seen that the parts 9 and 10 will fit snugly about the body of the wearer and yet permit free flexure between 5 said cuff and the trousers or the other body garment.

In Fig. 3 of the drawing, I have shown a slight modification wherein the cuff or band 13 is made from a straight, woven or knitted 10 tubular body, one end being folded inwardly to form an inner part 14, similar to the part 9, and the outer part 15 extends at its upper end beyond the end of the part 14 to form an 15 attaching flange portion 16 which is attached to the leg band 17 of the trousers or other support 18 as seen at 19. The upper edge 14^a of the inner part 14 is stitched to the part 15 as seen at 20, the stitching being such as to 20 permit the free expansion and contraction of the cuff or band and also preferably of such form as to be invisible externally of the cuff. In this construction, the same result is accomplished as in the structure shown in Figs. 1 25 and 2, the flange 16 permitting relative flexure between the garment and the cuff or band proper for the reasons before stated.

It will be understood that while I have 30 shown my invention as applied to the leg portions of a pair of knickers, the same may be applied to garments of other kinds and classes; and it will also be understood that my invention is not necessarily limited to any 35 particular type of material employed in the formation of the cuff or band, nor to any specific manner of attaching the inner and outer parts thereof, and various changes in and modifications of the construction herein shown and described may be made within the 40 scope of the appended claims without departing from the spirit of my invention or sacrificing its advantages.

Having fully described my invention, what I claim as new and desire to secure by Letters Patent, is:

1. As an article of manufacture, a cuff composed of a relatively long, double wall, tubular body of knitted material, the inner and outer walls of the cuff being integrally joined 50 at one end of the cuff, said cuff having elastic properties, the end of one wall of the cuff extending beyond the end of the other wall to form an annular attaching part of single wall thickness, facilitating the attachment of the 55 cuff to a garment, and the free edge of the shorter wall being attached to the longer wall by a circumferential line of stitching capable of expansion and contraction.

2. A cuff for knickers, comprising a tubular body of knitted material having elastic 60 properties, said body being of unitary construction and consisting of a relatively long cuff portion proper and a short attaching part, said cuff portion being of double wall 65 thickness, the upper end of the inner wall be-

ing attached to the outer wall adjacent said attaching part by a circumferential line of stitching capable of expansion and contraction, the said attaching part being continuous with the outer wall and being flared upwardly and outwardly to facilitate the attachment of said part to the leg encircling band of a pair of knickers.

In testimony that I claim the foregoing as my invention I have signed my name this 75 12th day of March, 1930.
